Attorney

UNITED STATES PATENT OFFICE.

WESLEY HAMM, OF DOLGEVILLE, NEW YORK.

HANDLE FOR BASKETS, SATCHELS, AND LIKE CONTAINERS.

Application filed April 10, 1922. Serial No. 551,330.

To all whom it may concern:

Be it known that I, WESLEY HAMM, a citizen of the United States, residing at Dolgeville, in the county of Herkimer and State 5 of New York, have invented certain new and useful Improvements in Handles for Baskets, Satchels, and like Containers; and I do hereby declare the following to be a full, clear, and exact description of the invention, such as will enable others skilled 10 in the art to which it appertains to make and use the same.

This invention relates to a handle for a basket, satchel, valise and like case and aims 15 to provide an article of this nature which may be easily and cheaply applied and which is light efficient and cooling to the hand.

Other objects and advantages will be apparent and suggest themselves as the nature 20 of the invention is understood.

While the drawings illustrate an embodiment of the invention, it is to be understood that in adapting the same to meet different conditions and requirements, various changes 25 in the form, proportion and minor details of construction may be resorted to without departing from the nature of the invention.

Referring to the accompanying drawings forming a part of the application,

30 Figure 1 is a perspective view of a basket provided with handles embodying the invention,

Figure 2 is a diagrammatic view of the invention, and

35 Figure 3 is a detail view showing the manner of construction.

Corresponding and like parts are referred to in the following description and designated in the several views of the drawings 40 by like reference characters.

The numeral 1 designates a basket which is representative of the class of devices for which the invention is designed, it being understood that the handle is adapted for a 45 satchel, valise, or analogous case.

The handle consists of a strip 2 of suitable material having an intermediate and end portions separated by means of slits 3, the portions 4 intermediate the slits 3 being of

any desired length to extend around the 50 parts to which the handle is attached. In the present instance, the numeral 4 designates the reinforcement or binding at the upper edge of the basket and the handles are attached thereto by folding or doubling the portions 55 4 of the strip 2 therearound. After the parts 4 of the strip 2 have been engaged with the basket, or analogous article, the divided portions of the strip bordering upon the slits 3 are brought together and are made secure by 60 means of a binder 5 which may consist of a length of cane, reed or other suitable material which is adapted to be woven about the parts of the strip 2 bordering upon and separated by the slits 3. In this manner said 65 portions are connected and the folded portions made secure. The manner of applying the handle will depend largely upon the character of the article to which it is attached and the character of the material is 70 not essential and will depend upon the finish of the handle and the article to which it is attached.

What is claimed is:

1. A handle of the character and for the 75 purpose herein stated, the same comprising a member folded upon itself and having the fold or bight engaging the article to which the handle is applied, and having the portions adjacent the fold divided, and a binder 80 woven about the divided portions and serving to connect the same and the folded parts.

2. A handle for a satchel or analogous article, the same consisting of a strip comprising longitudinally divided portions and intermediate portions intact and folded about the part of the satchel to which the handle is attached, the folded portions being brought together, and a binder woven about the longitudinally divided parts to connect 90 the same and the folded portions of the strip.

In testimony whereof I affix my signature in presence of two witnesses.

WESLEY HAMM.

Witnesses:

ELI MARKER,
CARL R. GREENLER.
